INVENTOR,
John E. Burns,
BY
James P. Duhamel,
ATTORNEY.

UNITED STATES PATENT OFFICE.

JOHN E. BURNS, OF FLUSHING, NEW YORK.

DENTAL CASTING-MACHINE.

1,233,182.

Specification of Letters Patent. Patented July 10, 1917.

Application filed April 7, 1916. Serial No. 39,574.

To all whom it may concern:

Be it known that I, JOHN E. BURNS, a citizen of the United States, and resident of Flushing, in the county of Queens and 5 State of New York, have invented certain new and useful Improvements in Dental Casting-Machines, of which the following is a specification.

This invention relates to dental casting machines and consists of means for supporting a flask in which the mold is prepared for the casting and a cap adapted to be closed down thereon so that compressed air may be admitted to the flask and the casting cooled under compression, as will be 10 more fully described in the following specification, set forth in the claim and illustrated in the accompanying drawings, wherein:

Figure 1 is a side elevation of the device.
Fig. 2 is a similar view of a modified form.

Fig. 3 is a side elevation of the device constructed for either means of operation and 25 showing in dotted lines its adaptability for being worked by either hand or foot.

Fig. 4 is a sectional view of the preferred form of flask.

Fig. 5 is a plan view of the base for the 30 flask.

Fig. 6 is an underneath view of the same.

Fig. 7 is a sectional view of the flask and cap.

Fig. 8 is a plan view of a modified form 35 of the base.

The object of this invention is to provide a means for subjecting a flask with a dental mold, such as a crown, a bridge or a plate, to the action of compressed air while the 40 molten metal is in the process of cooling and hardening, and for this purpose the flask which is made of several parts, is placed in a frame as shown in several of the views and a cap secured on the upper end of the same 45 through which the air is admitted to the flask.

The cap 10 is carried at the lower end of a pipe 11 which is adapted to receive compressed heated air from any desired source 50 and the pipe is also fitted in an overhanging arm 12 of a frame 13 supported on a table 9 and either permanently, as shown

in Figs. 1 and 3, secured by the set screw 14 or adapted to slide vertically as shown in Fig. 2.

When the pipe and cap are rigidly secured 55 the flask is carried by a movable platform 15 having guides 16 playing through perforations 16' and a central stem 17, the guide rods passing through a plate 18 which 60 is part of the frame, and the stem being connected by means of the link 19 with a hand lever 20. By dotted lines in Fig. 3 is shown how either form of lever is adapted to be applied to the machine to bring the cap and 65 flask together.

By this means the flask is moved to and from the cap and a gasket between the two as shown in Fig. 7, may secure an air tight fitting while the compressed air is admitted 70 by opening the cock 21.

The flask may be rectangular in shape or round as shown in Figs. 4 and 7 and in which instance the flask 22 is seated in a base 23 and has a cover 24 upon which the gasket 75 25 is placed and on this the cap 10 is forced. Within the flask is placed a ring 26 in which the two sections of the mold are formed, and leading from the lower end of the flask is a nipple 27 adapted to allow the escape of 80 air through the perforations 28 in the base 23. The base has a cavity 29 in its lower side and outlets 30 for the escape of the air.

In order to operate the cap and force it down upon the flask a foot lever 31, as 85 shown in Fig. 2 may be used and the cap may carry on its upper side a plate with arms 32 having depending rods 33 also passing through the perforations 16' when the platform 15 is removed and united by a 90 plate 34 and connected with the lever 31 by means of the link 35. As will be seen in Fig. 3 either form of lever or means for bringing the cap and flask together may be used, the parts used in Fig. 1 dropping 95 apart by gravity while those of Fig. 2 are separated by the springs 36.

While a rectangular flask may be used as in Figs. 1 and 2 and with a base 37 having perforations 38 as shown in Fig. 8, it is obvious that the round flask shown separately 100 may be used in either Figs. 1 or 2.

It is evident that the parts may be otherwise arranged and modified without depart-

2
ing from the essential features above described or from the scope of the appended claim.

What I claim as new is:

- 5 In a dental casting machine, the combination with a table having perforations, of a base plate with guide rods extending through the perforations, a stem depending from the plate, a lever beneath the table, a

link connecting the lever and stem, a flask 10 on the base plate, and a cap at the end of a compressed air pipe and adapted to fit the top of the flask.

Signed at New York, in the county of New York and State of New York, this 23d 15 day of March, A. D. 1916.

JOHN E. BURNS
